ALEXANDER CONSTANTINE IONIDES, JR., OF LONDON, ENGLAND.

GASEOUS COMBUSTION.

1,347,955.

Specification of Letters Patent. Patented July 27, 1920.

Application filed August 1, 1918. Serial No. 247,775.

To all whom it may concern:

Be it known that I, ALEXANDER CONSTANTINE IONIDES, Junior, a subject of the King of Great Britain and Ireland, residing at 5 34 Porchester Terrace, London, W. 2, England, have invented certain new and useful Improvements in or Relating to Gaseous Combustions, of which the following is a specification.

- 10 This invention relates to gaseous combustion of the type in which a combustible gaseous fluid and supporter of combustion, such as gas and air, are both conveyed in separate conduits at pressures bearing a constant relationship to one another to the desired position and mingled prior to combustion of the mixture in the correct proportions to obviate a substantial residue of a constituent.
- 15 In connection with multi-burner heating devices, I have already used a distribution system for combustion as above in which each burner is fitted independently with means for adjusting by the area of controlling orifices the proportions of the constituents in the mixture at that point, which adjustment having been once made at the maximum calorific value of the gas, is not altered for the minor variations in quality 20 of the gas which may at any time occur during working. In order, however, to still maintain substantially exact proportions during such minor variations, the main conduits which supply all the burners in common are one or both provided with adjusting means by which temporary corrections affecting all the burners simultaneously can be made.

Now I have found that the foregoing system of adjustment may under ordinary practical conditions be given a much wider scope and extended to, say, a complete system of gas lighting or to a series or bay of furnaces or other heating appliances where, 25 although the average consumption is not subject to large fluctuations, considerable variations may from time to time occur. By this means it is possible to place any large source of demand under the superintending control of a single responsible individual who by, say, reference to a test flame as hereinafter described, a guide, or any ordinary kind of light, or by other

means, may effect adjustment to counteract unavoidable variations in the quality of the 55 gas, which variations would otherwise lead to great loss of efficiency.

When experimenting with combustible mixtures, great difficulty has been experienced in providing a simple means for determining a neutral mixture, namely, a mixture of which the products of combustion 60 will contain neither an excess of carbon nor an excess of oxygen.

Now I have found that although mixtures of an ordinary coal gas and air when issuing under a moderate pressure, say $1\frac{1}{2}$ water gage, into the atmosphere from a small parallel orifice or jet will not continue to burn when the proportion of air to gas 65 appreciably exceeds three to one, yet by suitably flaring or coning the mouth of a bad heat conducting orifice, or by heating the mixture to a suitable extent combustion on issue will easily continue with much 70 weaker mixtures up to, or exceeding seven of air to one of gas.

A mixture of one and a half of air to one of an ordinary London coal gas gave under the above conditions a long flame 80 having a central extended cone of greenish color of a clearly defined length, which cone shortened as the proportion of air in the mixture was increased until it became a minimum which in this case was half of 85 the length first observed. The proportions of air to gas at this point were three and a half to one.

The central greenish cone up to this point 90 had been surrounded by a sheath of reddish-yellow color of a maximum diameter at about the middle of its length, which gradually decreased in thickness and length until at a ratio roughly of three and three quarters of air to one of gas the outline of 95 the cone and the exterior of the sheath merged into the single outline of a flame of a faint blue color and gradually tapering form, slightly longer than the above minimum cone.

Continuing to increase the quantity of 100 air in the mixture, the characteristic of a single outline bluish flame was maintained, increasing in length until at seven parts of air to one of gas the flame was double its 105 minimum length.

Proceeding again in the reverse direction, by reducing the proportion of air in the mixture, it was noted that the definite re-appearance of a distinct sheath and greenish yellow cone in the flame coincided with the proportion of about four of air to one of gas. It was thus evident that the alteration in the character of the flame and its minimum length coincided with proportions of gas and air which gave a neutral mixture for the gas under consideration, corresponding to maximum efficiency combustion in a closed furnace, and that the relative lengths of the cone and flame also indicated further defined proportions in either an oxidizing or in a reducing mixture. The measurements of cone and flame lengths vary with the quality of the gas, and the pressure of the incoming mixture.

20 The object of the present invention is to provide improved means for controlling a gaseous fuel supply system.

A further object of the invention is to apply the hereinbefore described phenomena 25 to the determination of the proportions of a combustible gaseous mixture.

The invention consists in a system for supplying gaseous fluids such as gas and air separately through suitable main conduits 30 to any number of combustion appliances, in which a supply of gas is governed to prevent a predetermined pressure being exceeded and a supply of air is provided at a pressure always in excess thereof, or vice versa, 35 said supplies of elastic fluids being further controlled by a pressure-balancing device to maintain a definite relationship between their pressures, and means being also provided for compensating for the variations in 40 the quality of the gas by adjustment of the supply to the main conduits of one or both of the fluids.

The invention further consists in a system as above indicated in which a governor 45 on the gas supply prevents a predetermined pressure being exceeded and further control of the fluids is effected within very narrow limits by a sensitive pressure balance having balanced valves actuated by a movable partition member such as a sensitive bell or diaphragm subjected on opposite sides to the air and gas pressures, adjustment preferably by means of valve control on the air conduit at the outlet of the pressure balance 50 being also provided for compensating for variations in the quality of the gas.

The invention further consists in a system according to one or both of the preceding paragraphs in which the gas and air are 60 combined at the burners of the combustion appliances in substantially the correct proportions for combustion by orifices primarily adjusted in accordance with the pressures and not easily afterward disturbed, 65 said air and gas being subsequently thor-

oughly mixed prior to reaching the ignition zone.

The invention further consists in a method of determining the proportions of the constituents in a combustible gaseous mixture 70 by observation of the character and dimensions of a flame produced by burning in the atmosphere, a jet thereof issuing under a constant moderate pressure from a small and preferably flared orifice. 75

The invention further consists in heating on its way to a small orifice a combustible gaseous mixture at a moderate constant pressure to a temperature at which a mixture of the required proportions will burn 80 when issuing into the atmosphere from such an orifice and utilizing observations of the character of the flames resulting from the combustion under corresponding conditions of mixtures of known proportions to obtain 85 the desired proportions in the mixture under consideration.

The invention further consists in a device for determining the proportions of the constituents in a combustible gaseous mixture, 90 said device comprising a small orifice for providing a jet of the combustible mixture issuing into the atmosphere, means for heating the mixture if necessary on its way to such orifice, and means for observing the 95 character of the flame produced by combustion of such jet of mixture, under a given pressure.

The invention further consists in a device according to the preceding paragraph 100 in which a jet of mixture issues from a preferably flared orifice at the end of a horizontally disposed tube which may be heated externally if desired, and a horizontal hollowed shielding screen positioned below the 105 flame produced by combustion of said jet is darkened, and may be provided with a pointer, markings, or like means to facilitate observation of the flame.

The invention also consists in the improved method of and or means for determining and adjusting the proportions of the constituents in a combustible gaseous mixture as hereinafter indicated. 110

Figures 1 and 2 show a more or less diagrammatic plan and elevation partially in section of one form of supply system in accordance with the invention. 115

Fig. 3 is a section of one form of mixture cock with adjustable orifices at the mixing point. 120

Figs. 4 and 5 are longitudinal and cross sections of one form of the flame test appliance and

Fig. 6 shows a modification of the test 125 appliance.

In carrying one feature of the invention into effect in a convenient form as shown by way of example in the drawings, a supply of gas at any convenient pressure in excess 130

of possible requirements is passed from any blower or pressure device 1 through any known floating bell or the like gas governor 2 or other suitable apparatus for governing the pressure of the gas which is so adjusted that some predetermined pressure within the limits of the supply will not be exceeded.

An air supply is provided by a fan 3 or other means at a pressure which will not be 10 lower at any time than the governed pressure of the gas.

The supplies of the two fluids are passed through a pressure-balancing device 4, preferably of the type described in British Patent Specification No. 110568, in which the movement of a sensitive bell 4^a or diaphragm or partition subjected upon opposite sides to the pressures of the air and gas operates balanced valves 4^b and 4^c controlling the passage of the fluids through the apparatus.

The supply mains 5 and 6 to the system of furnace, lighting or other burners 7 comprising in the embodiment illustrated an installation of furnaces of the type described in American application, Serial No. 137885, lead directly from the outlets of the pressure balance 4, and upon one or both of these mains ordinary stop or like adjustment valves 8 and 9 are provided, the adjustment being preferably made upon the air main alone by a valve 8 where the greatest niceness of adjustment is desired.

The burners 7 are fed by separate connections from both the gas and air mains 5 and 6, the proportions of the mixture being adjusted in accordance with the relative pressures of the fluids by means of adjustable orifices 10^a, 10^b in mixing cocks 10 or the like, as shown in Fig. 3 and the constituents being thoroughly mixed prior to reaching the ignition zone of the burner.

In such a system the gas governor 2 is so set that a suitable predetermined gas pressure shall not be exceeded and the pressure balance 4 is arranged to maintain equal pressures of, or any desired relationship within the scope of the device between the pressures of the two fluids. The burner or mixer orifices 10^a, 10^b are primarily adjusted to pass the desired quantities for a correct mixture at the determined pressures and where the greatest niceness of adjustment is required as above at the maximum calorific value of the gas, all of the burner mixers in the system, preferably including that for a flame, light, or other test burner 11, being adjusted under the same conditions.

Where the system comprises lights, one 60 may be fixed at a convenient position to act as a guide, or a guide light may be added to any system which comprises only furnaces or other heating appliances. Where, however, the condition of the furnace flame, 65 yiz., oxidizing, reducing or neutral, is of

importance, a test flame of the type herein indicated is preferably employed at 11. When once the burner orifices 10^a, 10^b have been adjusted they should not be altered by the workman or other persons without authority, further adjustment under working conditions in order to provide for the slight unavoidable variations in the quality of the gas being effected by adjustment of the air supply to the entire system by means of a 75 valve or the like 9 as hereinbefore described. When effecting such temporary adjustments the guide light or other determining means 11 as indicated will preferably be used by the superintending responsible person as an 80 indication in order to establish correct conditions in the mains.

In a complete works in which pieces of apparatus requiring widely different pressures are installed, such apparatus may be 85 grouped in order to place all those requiring substantially similar pressure conditions under one system of control. A main supply of gas may be provided at a pressure high enough for the maximum requirements, and the different pressures required in the separate system can be controlled by gas governors positioned at the inlets to the pressure balances of the respective systems. An air supply at the maximum necessary 90 pressure may be taken to all the balances without further control, as the pressure of one of the constituents entering the pressure balance being correct, the pressure of the other constituent in order to maintain a desired constant relationship will be automatically controlled by the pressure balance itself. If the pressures of gas and air in the mains are high enough, all the heating devices can be given greater elasticity by a 95 proportional valve being introduced to those requiring that elasticity.

The burners are preferably inclosed and so arranged that escape of the products of combustion into the atmosphere is at a 100 point below the level of the combustion zone in order to avoid the suction effect of chimneys or equivalent devices. By this means it is assured that no external air can possibly obtain access to the burner or other 115 parts of the furnace or combustion appliance to upset the proportions of the mixture.

In carrying the second feature of the invention into effect in one simple piece of 120 apparatus given by way of example, the mixture formed from separate supplies of gas and air maintained at equal or constantly related moderate pressures is conveyed to the apparatus through a tap or 125 like control means by which the exact pressure on the jet may be regulated.

In the arrangement of the test flame 11 shown by way of example in Figs. 4 and 5, a is a trough or casing formed of metal or 130

other suitable material and having the greater portion of its top open, as shown at *b*.

5 Into one end of the casing *a* is fastened a back-flash extinguishing device *c* preferably of the type described in my British Patent No. 12346 of 1912, carrying at its outer end a T-piece *d* to one branch of which is attached a stop-cock *e* surmounted by a 10 pressure gage *f* suitable for recording moderate pressure and to the other branch of which is attached a stop-cock *g* provided with an extension *h* adapted to receive a rubber tube connection *i*.

15 The end of the back-flash extinguisher *c* projecting within the casing *a* is provided with a short length of rubber tubing *j* into which is inserted the bulbed end of a silica glass tube *k* the other end of which 20 is internally coned or flared, as shown at *l*. This glass tube may conveniently be about three inches long and one-eighth bore, with the flared end opening from one-eighth to one-quarter diameter in a length of about 25 one-quarter of an inch.

Fastened to the opposite end of the casing *a* and projecting to beneath the flared end of the tube *k* is a shallow trough or shield *m* which may conveniently be formed 30 to a semicircle in cross-section, as shown in Fig. 5. This screen is preferably darkened upon its upper surface in order to render the flame more visible and its edge may be provided with suitable markings or 35 other means for determining the length of the flame.

Beneath the tube *k* the casing *a* may be provided with a pocket *n* closed by a lid *o* and in which the pressure gage *f* may be 40 inserted when not in use to protect it from injury.

When using the apparatus, the rubber tube *i* is connected to a furnace or other burner which is to be tested or it may be connected to the outlet of any mixing appliance in which a mixture is formed from 45 separate supplies of two constituents such as gas and air maintained at equal or constantly related moderate pressures, further adjustment of the pressure at the jet and upon the pressure gage being effected by adjustment of the stop cocks *e* and *g* as desired, a pressure of a few tenths of an inch water gage being generally a convenient one with which to operate. The jet of 50 issuing mixture is then lighted and the proportions adjusted until the desired result is obtained by observation of the flame as hereinbefore indicated.

60 In a modification of the foregoing construction, the apparatus may conveniently take the form of an upright pipe, having a connection at its lower end and a tap; also a pressure gage and a backflash extinguisher 65 as already described.

To the outlet of the backflash extinguisher is fitted a length of horizontal pipe *k'*, say a silica glass tube, of about three inches in length and one-sixteenth diameter bore, or other suitable dimensions, and below this 70 pipe there is provided a spirit lamp *Z* or other convenient heating device capable of raising the temperature of the mixture passing through the pipe *k'* at a point sufficiently far from the outlet end to prevent the flame of the lamp interfering with the flame produced at the issuing jet of mixture. 75

Beneath the orifice from which the mixture issues at the end of the pipe *k'* is a 80 horizontal hollow or concave shielding screen *m'*, long enough to cover any length of flame produced by the pressure of mixture employed in the apparatus. This screen may be darkened and fitted at one of 85 its edges with markings.

This screen, in addition to facilitating observation of the flame also acts to shield it against any currents of air coming from beneath and tending to cause undesirable 90 upward deflection of the flame.

In operation, mixture at a suitable pressure is supplied to the apparatus, the pressure being further adjusted by means of the tap until the desired reading, say, of 95 a few tenths of an inch water pressure, is obtained on the pressure gage. The spirit lamp or like heating means when used is then put in operation and the jet of issuing mixture lighted and the proportions adjusted 100 until the desired result is attained by observation of the flame, as hereinbefore indicated.

By means of this second feature of the invention, the proportions of gas and air in 105 the mixture can be easily and rapidly adjusted to give either a neutral, reducing or oxidizing flame. Such adjustment being effected by a portable apparatus successively applied at each furnace during the same period that the permanent apparatus is correctly adjusted and operating at the test point 11 of the system. When a change in the quality of the gas shows undesired conditions at the permanent apparatus, a correction is made by adjustment on the mains 115 when the supply to all the furnaces will be simultaneously corrected.

Modifications in the arrangement of the system or in the apparatus and manner of 120 using the same may be introduced, and automatic means for recording the results added, without in any way departing from the spirit of this invention.

Having now fully described and ascertained my said invention and the manner in which it is to be performed, I declare that what I claim is:—

1. A system for supplying two gaseous fluids such as gas and air to any number of 130

- combustion appliances, comprising in combination a supply of one of said fluids, say for example the gas, governed to prevent a predetermined pressure being exceeded, a supply 5 of another fluid, such as air at a pressure always in excess of said gas, a pressure balancing device by which said supplies are further controlled to maintain a definite relationship between their pressures, and 10 means for compensating for the variations in the quality of the gas by further adjustment of the controlled supply of one or both of the fluids.
2. A system for supplying two gaseous 15 fluids such as gas and air to any number of combustion appliances comprising in combination a governor on the gas supply preventing a predetermined pressure being exceeded, a sensitive pressure balance having balanced valves actuated by a movable partition member such as a sensitive bell or 20 diaphragm subjected on opposite sides to the static air and gas pressures to control the relationship of the pressures of the fluids within very narrow limits; valve control means on one of the supply mains at the outlet of the pressure balance for compensating 25 for variations in the quality of the gas and mixing means having orifices controlled by members not easily afterward disturbed, which are primarily adjusted in accordance with the pressure to give a mixture which 30 is correctly proportioned prior to reaching the ignition zone of the combustion appliances.
3. A system for supplying two gaseous 35 fluids, such as gas and air, to any number of combustion appliances comprising in combination a supply of one of said fluids, say for example gas; a gas governor to prevent a predetermined pressure being exceeded, a supply of the other fluid such as air at a pressure always in excess of the said gas, a pressure balancing device by which said supplies are further controlled to maintain 40 a definite relationship between their pressures, means for compensating for the variations in the quality of the gas by further adjustment of the controlled supply of at least one of the fluids and mixing means 45 having orifices controlled by members not easily afterward disturbed, which are primarily adjusted in accordance with the pressures to give a mixture which is correctly proportioned prior to reaching the ignition zone of the combustion appliances.
4. A system for supplying gaseous fuel 50 and air to a number of distributed combustion appliances comprising in combination means for providing a supply of gaseous fuel at a moderate pressure, means for providing a similar supply of air, means for maintaining a constant relationship between the pressures of said two supplies and a signal light or test flame situated at a convenient station and individually adjusted simultaneously with all the other burners of the system to comply with desired observed conditions at a given calorific value of the gaseous fuel and a determined ratio 55 between the pressure of the two gaseous fluids, so that upon alteration of the calorific value all the burners may be returned to the desired conditions by adjusting a single valve or valves on one or both of the supplies until the signal flame is restored to its 60 original state.
5. A system for supplying two gaseous fluids such as gas and air to any number of combustion appliances comprising in combination a governor on the gas supply preventing a predetermined pressure being exceeded; a sensitive pressure balance having balanced valves actuated by a movable partition member such as a sensitive bell or 65 diaphragm subjected on opposite sides to the static air and gas pressures to control the relationship of the pressures of the fluids within very narrow limits; valve control means on one of the supply mains at the outlet of the pressure balance for compensating 70 for variations in the quality of the gas and mixing means having orifices controlled by members not easily afterward disturbed, which are primarily adjusted in accordance with the pressure to give a mixture which 75 is correctly proportioned prior to reaching the ignition zone of the combustion appliances.
6. A method of obtaining exactly proportioned mixtures of gaseous constituents such as gas and air adapted for combustion, consisting in providing separate supplies of said constituents at moderate pressures bearing a constant relationship to one another, mixing said constituents in proportions regulated by controlling apertures, adjusting the pressure of the resulting mixture to a definite determined value and observing the nature of the flame produced, by burning in the atmosphere a jet of the mixture issuing 80 from a small and preferably flared orifice.
7. A method of obtaining exactly proportioned mixtures of gaseous constituents such as gas and air adapted for combustion, consisting in providing separate supplies of said constituents at moderate pressures bearing a constant relationship to one another, mixing said constituents in proportions regulated by controlling apertures, adjusting the pressure of the mixture to a 85 definite determined value and observing the nature of the flame produced, by burning under conditions adapted to maintain an issuing jet of the mixture at a temperature sufficient to insure continued combustion in 90 the atmosphere.
8. A method of obtaining exactly proportioned mixtures of gaseous constituents such as gas and air for combustion consisting in providing separate supplies of said constituents at moderate pressures, bearing a constant relationship to one another, mixing said constituents in the proportions regulated by controlling apertures, adjusting the pressure of the mixture not to exceed one 95

- inch water gage and burning in the atmosphere a jet of the mixture issuing from a small orifice of refractory material having a flared or coned mouth piece.
- 5 9. In combination in apparatus for obtaining exactly proportioned mixtures of gaseous constituents such as gas and air adapted for combustion, means for providing a correctly proportioned supply of mixture at a moderate pressure, means for emitting a small jet of the mixture into the atmosphere, and means for maintaining said jet at such a temperature as to insure continued combustion.
- 10 15. 10. In combination in apparatus for obtaining exactly proportioned mixtures of gaseous constituents such as gas and air adapted for combustion, means for providing a correctly proportioned supply of mixture at a moderate pressure, a small orifice for emitting a jet of the mixture into the atmosphere, means preferably comprising a flared mouth piece to said orifice for maintaining said jet at such a temperature as to insure continued combustion and a hollowed shielding screen positioned closely adjacent the side of said jet and adapted to facilitate observation thereof.
- 15 20. 11. In combination in apparatus for obtaining exactly proportioned mixtures of gaseous constituents such as gas and air adapted for combustion, means for providing a correctly proportioned supply of mixture at a moderate pressure, a small orifice for emitting a horizontal jet of the mixture into the atmosphere, means preferably comprising a flared mouth piece to said orifice for maintaining said jet at such a temperature as to insure continued combustion,
- 25 30. 40. 12. A method of obtaining exactly proportioned mixtures of gaseous constituents such as gas and air for combustion consisting in providing separate supplies of said constituents under moderate pressure, maintaining a constant relationship between the pressures of said constituents by controlling said supplies by valve means actuated by a movable partition subjected upon opposite sides to the controlled pressures, mixing said constituents in proportions regulated by controlling apertures, adjusting the pressure of the resulting mixture to a definite determined value, and observing the nature of the flame produced by burning in the atmosphere a jet of the mixture issuing from a small and preferably flared orifice.
- 35 45. 50. 55. 60. 13. A method of obtaining exactly proportioned mixtures of gaseous constituents such as gas and air for combustion consisting in providing separate supplies of said constituents under moderate pressure,
- 65 maintaining a constant relationship between the pressures of said constituents by controlling said supplies by valve means actuated by a movable partition subjected upon opposite sides to the controlled pressures, mixing said constituents in proportions regulated by controlling apertures, adjusting the pressures of the mixture, not to exceed one inch water gage, and burning in the atmosphere a jet of the mixture issuing from a small orifice of refractory material having a flared or coned mouth piece.
- 70 75. 14. A method of obtaining exactly proportioned mixtures of gaseous constituents such as gas and air for combustion consisting in providing separate supplies of said constituents, governing the pressure of one supply so that the pressure of the other will under all ordinary conditions of variation be the greater, automatically maintaining a constant relationship between the pressures of said constituents by exerting a checking or throttling action upon said supplies in conjunction with submitting a movable partition, which actuates the throttles to the modified pressures of said constituents acting upon opposite sides thereof, providing for further optional control of one of said supplies and applying combustion indicating means to obtain any desired exact proportions in a mixture of said constituents.
- 80 85. 90. 95. 100. 105. 110. 115. 120. 125. 130. 14. 15. A method of obtaining exactly proportioned mixtures of gaseous constituents such as gas and air for combustion consisting in providing separate supplies of said constituents, governing the pressure of one supply so that the pressure of the other will under all ordinary conditions of variation be the greater, automatically maintaining a constant relationship between the pressures of said constituents by exerting a checking or throttling action upon said supplies in conjunction with submitting a movable partition which actuates the throttles to the modified pressures of said constituents acting upon opposite sides thereof, and providing for further optional control of one of said supplies.
16. A method of obtaining exactly proportioned mixtures of gaseous constituents such as gas and air for combustion, consisting in providing separate supplies of said constituents, automatically maintaining a constant relationship between the pressures of said constituents by exerting a checking or throttling action upon said supplies in conjunction with submitting a movable partition, which actuates the throttles to the modified pressure of said constituents acting upon opposite sides thereof, providing for further optional control of one of said supplies, and applying combustion indicating means to obtain any desired exact proportions in a mixture of said constituents.

17. A method of obtaining exactly proportioned mixtures of gaseous constituents such as gas and air for combustion consisting in providing separate supplies of said constituents, governing the pressure of one supply so that the pressure of the other will under all ordinary conditions of variation be the greater, automatically maintaining a constant relationship between the pressures of said constituents by exerting a checking or throttling action upon said supplies in conjunction with submitting a movable partition to the modified pressures of said constituents acting upon opposite sides thereof, providing for further optional control of one of said supplies, applying temporary combustion indicating

means to show the character of a mixture consumed in one of any number of furnace or other combustion appliances operating under desired conditions, simultaneously adjusting a mixture to produce like results in a permanent combustion indicating means and subsequently in the case of variation in the gas supply utilizing the further optional control to restore the desired conditions of combustion from observation of the permanent indicating means. ²⁰ ²⁵

In testimony whereof I have signed my name to this specification.

ALEXANDER CONSTANTINE IONIDES, JR.
